UNITED STATES PATENT OFFICE.

WILLIAM LUCK AND CARROLL O. KLINGE, OF WATERTOWN, SOUTH DAKOTA.

SHOE-Straightening INSOLE AND ARCH SUPPORT.

Application filed August 28, 1923. Serial No. 659,790.

To all whom it may concern:

Be it known that we, WILLIAM LUCK and CARROLL O. KLINGE, citizens of the United States, residing at Watertown, in the county 5 of Codington and State of South Dakota, have invented certain new and useful Improvements in Shoe-Straightening Insole and Arch Supports, of which the following is a specification, reference being had there- 10 in to the accompanying drawings.

This invention relates to a shoe straightening insole and arch support, and the object of the invention is the construction of a simple and efficient straightening insole 15 for use in boots, shoes, or slippers, or the like.

Another object of the invention is the construction of a simple and efficient insole and arch support that will greatly help the 20 wearer's foot.

With the foregoing and other objects in view, our invention comprises certain novel combinations, constructions and arrangements of parts as will be hereinafter described, illustrated in the accompanying drawings, and more particularly pointed out in the appended claims.

In the drawings:

Figure 1 is a bottom plan view of our 30 shoe straightening insole.

Figure 2 is a view taken on line 2—2, Fig. 1, and looking in the direction of the arrows.

Figure 3 is a sectional view taken on line 35 3—3, Fig. 2.

Figure 4 is a sectional view taken on line 4—4, Fig. 2.

Figure 5 is a top plan view of our straightening insole and arch support, while 40 Figure 6 is a bottom plan view of the same.

Figure 7 is a sectional view taken on line 7—7, Fig. 5, and looking in the direction of the arrows.

Figure 8 is a plan view of another embodiment of the shoe straightening insole.

Referring to the drawings by numerals and particularly to Figs. 1 to 4, 1 designates the insole which comprises body 2, formed 50 preferably from a strip of leather and having on its bottom and at one side, a toe pad 3, and also on its bottom at one side of the heel a pad 4. On the toe portion of the insole, parallel with pad 3 and between the 55 edges of the insole is a recess 5. The pad 3 is for raising the outside of the ball of the

foot to throw the weight inward and strengthen the foot. The pad 4 is for raising the heel of the foot to throw the weight of the foot inward and strengthen the ankle. 60 The cut-away portion forming the recess 5, is for the ball of the foot to rest lower than the rest of the insole; this recess 5, formed by cutting away part of the leather, is very essential as by this the weight is more evenly distributed and does not merely all rest on the bottom of foot. 65

Referring to the embodiments shown in Figs. 5, 6 and 7: In these figures we have shown an insole 1, comprising a piece of 70 leather 2 having the toe pad 3 and the heel pad 4, as in Figs. 1 and 2. Further, the recess 5 is also employed but with this embodiment (Fig. 5) the leather, at the instep is split at one edge to form a pocket, into which a filler pad 6 is placed, as clearly shown in Fig. 7. The upper portion 7, of the split portion of the insole, is bowed upwardly, to form an arch support; the padded portion 8 also forms an arch support. 75

Referring to Fig. 8: In this figure we have shown the insole 1 formed of a leather strip 2 and provided with a depression or recess 9 in the middle of the toe pad 3 to receive the joint of the large toe and make the device comfortable. This pad 3 raises the ball of the foot and is designed for people who have a tendency to run over their 80 shoes on the inside; with this appliance the foot can be straightened and the ankle straightened enough in a very short time to entirely overcome the unsightly weakness and completely restore the foot to its normal condition. The device shown in Figs. 1 to 85

4 keeps the shoe straight because the ball of the foot rests in the "cutaway" or recess on the inside of the sole, and is raised on the outside, keeping the weight of the foot evenly balanced and also keeping the heel of the shoe straight thereby preventing people, who wear shoes over on the outside, from doing so and causing the heel and sole of the shoe alike to wear evenly, straight and not on one side or the other. 90

The shoe straightening insole and arch support shown in Figs. 5 to 7 has the same advantage as the devices shown in Figs. 1 to 4 and 8, and additional advantages as well. The arch support, built right into the insole, strengthens the arch of the wearer, and is the lightest and most com- 100 105 110

pact and durable way possible to build an arch support, because when placed inside of the shoe it cannot work out of place as the insole is fitted to the inside of the shoe.

5 While we have described the preferred embodiments of our invention, and have illustrated the same in the accompanying drawings, certain minor changes or alterations may appear to one skilled in the art to 10 which this invention relates, during the extensive manufacture of the same, and we, therefore, reserve the right to make such alterations or changes as shall fairly fall within the scope of the appended claims.

15 What we claim is:

1. An insole comprising a body, a heel pad upon one side portion of the heel end portion of said body, and a pad for the

ball portion extending along one side portion of the forward end portion of said body, a recess being provided for receiving the joint portion of the large toe to prevent excessive pressure thereon. 20

2. An insole comprising a body, a heel pad upon one side portion of the heel end portion of said body, and a pad extending along one side portion of the forward end portion of said body, the forward portion of the body at the position where the pad is secured thereto being provided with a 25 recess for relieving the inner joint of the 30 large toe from excessive pressure.

In testimony whereof we hereunto affix our signature.

WILLIAM LUCK.
CARROLL O. KLINGE.
